UNITED STATES PATENT OFFICE.

FRANKLIN C. HASSE, OF CONGRESS PARK, ILLINOIS.

RAIL-CUTTING DEVICE.

1,342,502.

Specification of Letters Patent. Patented June 8, 1920.

Application filed March 8, 1918. Serial No. 221,332.

To all whom it may concern:

Be it known that I, FRANKLIN C. HASSE, a citizen of the United States, and a resident of Congress Park, in the county of Cook and State of Illinois, have invented a certain new and useful Improvement in Rail-Cutting Devices, of which the following is a description, reference being had to the accompanying drawings, which form a part of my specification.

My invention relates to a device adapted for the purpose of cutting railroad rails, or other similar structural metallic beams or members; the device being especially adapted for use in connection with rails that have been laid or put into place.

The object of my invention is to provide a construction which is more especially intended to employ a cutting blow-pipe or torch, which is adjustably secured by the device to the rail and enables a quick and even cut to be obtained.

Another object of the invention is the provision of a device which may be quickly and readily adjusted to various sizes of rails, or other standard structural members, as will be apparent from the following detailed description of the accompanying drawings, wherein:

Figure 1 illustrates my improved device in side elevation attached to a T-rail.

Fig. 2 is a detail sectional view taken on the line 2—2 of Fig. 1 looking in the direction of the arrows.

Fig. 3 is an end elevation of my improved device, as disclosed in Fig. 1, clamped in operative position on a T-rail, with the latter shown partially cut.

Fig. 4 is a detail sectional view of a modified form of blow-pipe holding means.

In the particular exemplification of the invention, I have shown it applied to a well known type of T-rail indicated at A; the device being in place for the cutting operation, which, according to the disclosure made in Fig. 3, has been partially made; having been begun at the base of the rail and continued in a vertical direction, as shown at a.

The device comprises a main portion or frame 5 provided with downwardly presented ends 6 and 7; the distance between the downwardly presented ends being greater than the width of the head of a rail in order that the device may straddle the rail, with the ends of the frame disposed on opposite sides of the head of the rail, as

shown in Fig. 1. The end 7 is preferably tapered inwardly or arranged at an inclination toward the head of the rail so as to enable it to engage with the lower edge of the rail-head, as shown at 8 in Fig. 1. The end and portions of the main frame may be provided with suitable reinforcing ribs, as shown in the drawings, in order to give the necessary strength. The end 6 is not intended to engage with the rail, but is provided with the pivoted clamping member which comprises the lever 9 terminating in the cam-portion 10 which is adapted to be brought into clamping or wedging engagement with the adjacent side of the head of the rail, as shown in Fig. 1. The cam-portion 10 is readily brought into wedging or clamping engagement with the rail-head simply by the downward movement of the handle or lever-portion 9, about the pin 11 which forms a pivotal point for the lever on the end 6 of the main frame 5. In order to adapt the device to different widths or sizes of rails, the end 6 is shown provided with a plurality of pivot-receiving holes 12 for the pivot pin 11.

The opposite end of the main frame, 5, to-wit the end provided with the depending portion 7, also terminates in a guide-head 13 which is provided with an elongated vertically disposed slot, shown in dotted lines at 14 in Figs. 1 and 3, adapted to receive a suitable bolt or pin 15 whereby the bar or stem 16 is adjustably secured in position on the head-portion 13. The bolt or pin 15 is provided with suitable clamping means, as for example the nut and washer, indicated at 17 in Fig. 3, which enables the bar or stem 16 to be firmly clamped to the head 13 of the device. It is evident from the construction just described, that the bar 16, and the elements supported thereby, may be adjusted vertically by means of slot 14 in the head 13, thus adapting the device to rails of different heights.

The lower end of bar 16 terminates in a sleeve or hollow portion 18, adapted to be disposed in a direction lengthwise of the rail. This sleeve-portion 18 is adapted to receive the cylindrical shank or portion of an arm 19, which latter is intended to carry or pivotally support the cutting torch or blow-pipe, indicated at 20. The arm 19 is provided with an angular or bent portion, disposed substantially perpendicular to the longitudinal axis of the arm, as clearly

shown in Fig. 3; and this bent portion or end is of sufficient width to permit of a slot 21, being formed therein, which receives the blow-pipe clamping and holding members 5 now to be referred to. The blow-pipe holding members consist of an eye-bolt 22, the shank whereof is adapted to extend through a suitable bushing 23, see Fig. 2, which, with the shank of the eye-bolt, passes through 10 the slot 21 of arm 19. The bushing enables the eye-bolt 22 to be firmly locked or clamped in the desired position by means of the nut 24 which takes about the threaded end of the bushing 23 and engages with the side of 15 the arm 19, as clearly shown in Figs. 2 and 3; while the eye-bolt 22 is held in place against displacement by a suitable nut 25. The bushing 23 supports a transversely disposed member or saddle 26; the opposite 20 ends whereof are suitably grooved to receive the tip or nozzle end 27 of the blow-pipe or torch 20; the tip being seated in the grooves formed in both ends of the saddle, as clearly shown in Figs. 1 and 2, and there- 25 by held against any movement independent of the saddle.

The shank or arm 19 extends through the sleeve-portion 18 of the bar or stem 16, as clearly shown in Fig. 3, and the extended 30 end is provided with a suitable coil-spring 28; one end whereof bears against the end of the sleeve-portion 18, while the other end is engaged by the washer or member 29 held in place by a suitable nut 30 which screws 35 onto the threaded end of the shank of arm 19. It is evident from the construction shown that the tension of spring 28 may be regulated by screwing nut 30 in the proper direction. With a sufficient compression of 40 the spring induced by the screwing up of nut 30, a frictional relation between arm 19 and sleeve 18 is provided which will prevent the voluntary or free rotation of arm 19 in the sleeve-portion 18, while at the same time 45 permitting the arm 19 to be rotated in sleeve 18, by the application of sufficient force or pressure on the blow-pipe 20 by the operator.

The main portion or frame 5 of the device 50 is provided at an intermediate point with portion or loop 31, which is preferably formed integral with the main portion 5 and shown disposed at right angles thereto, so as to extend lengthwise of the rail when 55 the device has been put into place. The opposite end of the loop or portion 31 is disposed downwardly and terminates in a straddling or saddle portion 32 adapted to straddle or extend about the head of the 60 rail A, as shown in Fig. 3. The straddle or saddle end 32 of the loop-portion 31 may be provided with a reinforcing connecting rib 33 formed integral therewith and with the main portion 5 so as to give sufficient 65 strength and rigidity to the frame portion

of the device. As is evident from the construction shown, the straddle or saddle portion 32 will prevent any sidewise or wabbling movement of the device; while the loop-portion 31 will provide a proper handle or means for transporting the device 70 from place to place.

In practice, the device is placed on the head of the rail intended to be cut, at a point in proximity to the place where the 75 cut is to be made, by having the frame 5 extend transversely of the head of the rail, as shown in Fig. 1, and placing the same so as to bring the tapered or inclined side 8 of the end 7 in abutting relation with the side 80 of the head. The lever 9 is then moved downwardly so as to bring the cam-portion 10 into firm relation with the adjacent side of the head of the rail, as indicated in Fig. 1. In order to provide a proper clamping engagement with the rail operated on, adjustment of the clamping element, as previously 85 stated, is accomplished by placing the pivot pin 11 through the proper hole 12 at the end of the frame-portion. It is evident that the 90 adjustment of the clamping element just described need merely be altered where the head or upper end of the rail-section to be cut is of materially smaller transverse dimensions than that disclosed in Fig. 1, as 95 the clamping element is capable of clamping engagement without readjustment even though there may be slight variations in the transverse dimensions or sizes of the rail-head, as such variations will be taken 100 care of by the increasing radius of the wedging cam-portion 10 from pivot 11. With the device thus adjusted, the bar or stem 16 is then adjusted vertically by means of the clamp-nut 17 on the end of bolt 15 so as 105 to adjust the device to the height of the rail. While the device is being used for cutting similar sized rails, no further adjustment need be made after the adjustments just referred to have been completed; and 110 the device can be readily clamped to the rail through the single operation or movement of the lever 9 of the clamping element.

The eye-bolt 22 is drawn into firm relation with the bushing 23 and saddle 26 by 115 means of the nut 25, after the tip 27 of the blow-pipe 20 has been passed through the eye of the bolt. The screwing up of nuts 24 and 25 will cause the eye-bolt to force the nozzle of the blow-pipe into the grooves of the saddle-member 26, and thus prevent any movement of the nozzle of the blow-pipe relative to the saddle 26; while the saddle 26, in turn, will be held in firm frictional relation with the end of arm 19 by means of nut 24, 120 through the medium of the bushing 23. With the tension of spring 28 regulated so as to provide a sufficient frictional relation between the arm 19 and sleeve-portion 18, it 125 is apparent that the blow-pipe will be held 130

against movement except through the application of sufficient force by the operator on the blow-pipe; the frictional relation, however, permitting the tip or nozzle of the 5 blow-pipe to be oscillated or moved through the arc of a circle so as to direct the cutting flame in a progressive manner from the initial point, or point of beginning, to the final end of the cut to be made; as for example the tip of the blow-pipe may be rotated so as to direct the cutting flame in the 10 radii of a circle, as indicated by the dotted lines x, x', x'', x''', x'''' ; the swinging of the nozzle or tip of the blow-pipe being 15 accomplished by pressure on the handle of the blow-pipe. This swinging movement of the blow-pipe permits a cut to be completed, which I will assume has been begun at the 20 base of the rail, by a flame directed as indicated by the dotted line x , progressing upwardly and completed when the nozzle has been rotated so as to direct the flame in the direction of dotted line x'''' , thereby 25 completely cutting or severing the rail.

25 With the arm 19 extending toward one side of the main or frame-portion of the device, it is apparent that the frame portion will in no way interfere with the swinging movement of the blow-pipe so as to direct 30 the flame toward the adjacent edge of the rail-base, namely along the dotted line x .

In Fig. 4 I illustrate a modified form of the blow-pipe holding means, namely the blow-pipe nozzle-receiving portion of the 35 device. Instead of employing the saddle and eye-bolt construction shown in Fig. 2, the blow-pipe nozzle-holding means may be in the nature of an angle member 34, with one leg or side of the angle terminating in 40 a tapered sleeve portion 35. The opening through the sleeve-portion 35 is preferably tapered toward the tip of the sleeve so as to correspond somewhat with the taper of the nozzle of the blow-pipe; and the opposite 45 end of the opening is also slightly beveled as shown at 36 to receive the beveled base or butt-portion of the blow-pipe nozzle. With this construction, a firm holding relation is provided. With this form of holding 50 means, it is apparent that while the blow-pipe will be firmly held in place, the blow-pipe may also be oscillated in the sleeve-portion 35 so as to dispose the blow-pipe lengthwise of the rail and thus enable the 55 flame to be directed toward the upper part of the rail in situations where the ties or road-bed would otherwise interfere with the proper use of the device on laid rails. The other leg or side of angle member 34 is intended 60 to abut against the angularly disposed portion of arm 19 which is shown in section in Fig. 4; the side of member 34 being provided with a hole adapted to receive a short bolt 37, the head whereof takes 65 against the side of member 34, while the

threaded end of the bolt extends through arm 19 and receives a nut 38 whereby the member is removably secured in place.

The constructions shown permit the device to be quickly applied and secured to the rail to be cut and enable the blow-pipe to be swung into any position necessary to apply the cutting flame at the desired point on the element or rail to be cut; and while I believe the constructions to be the simplest embodiments of my invention, the same may be altered in certain respects within the scope of the claims without, however, departing from the spirit of my invention.

What I claim is:—

1. A device of the class described, comprising a frame consisting of a pair of rail-straddling portions and an intermediate loop or hand-receiving portion, one of the ends of the straddling portions being 85 adapted to engage beneath the rail-head, a wedging member pivotally secured to the opposite end of said straddling portions so as to oscillate vertically, said wedging member comprising a lever terminating in a 90 cam, the latter being adapted to form wedging engagement with the rail-head, a vertically disposed member adjustably secured to one end of said frame so as to depend along the rail side, a blow-pipe carrying element 95 rotatably mounted in the lower end of said vertically disposed member and adapted to rotate about a horizontally disposed axis, means whereby said element is yieldingly held in its adjusted relation with said vertically disposed member, and blow-pipe holding means comprising a socketed member and nozzle-seating saddle, the saddle and socketed member being adapted to have adjustable clamping relation with each other 100 and with said element.

2. A device of the class described, comprising a frame adapted to straddle a rail and having depending ends, one of the ends being formed to provide clamping relation 110 with the rail, means pivotally secured to the other end of the frame and adapted to swing into clamping relation with the rail-head when the means is oscillated, a vertically disposed member adjustably secured to the 115 first mentioned end of the frame and terminating at its lower end in a sleeve portion, a horizontally disposed arm rotatably mounted in said sleeve-portion, yielding means secured to one end of said arm and adapted 120 to provide a yielding frictional relation between said arm and sleeve-portion, and blow-pipe holding means secured at the free end of said arm, said means comprising a saddle member in which the nozzle of the 125 blow-pipe rests and a clamping member through which the nozzle extends, the saddle member and clamping member having contacting relation with each other.

3. A device of the class described, com- 130

prising a rail straddling frame, one end of the frame terminating in an integral rail-head engaging jaw, a second rail-head engaging jaw, adjustably pivoted to the other end of the frame, a vertically adjustable member secured to the first mentioned end of the frame, depending beneath the rail-head and terminating in a laterally disposed sleeve portion, a second member rotatably secured in said sleeve portion and disposed laterally beyond the frame side, means whereby said second member is frictionally held in its adjusted positions, and blow-pipe holding means adjustably secured to one end 15 of said second member.

4. A device of the class described, comprising a saddle portion adapted to fit over the head of a rail, one end of said portion

being formed to engage beneath the rail-head, a cam adjustably pivoted to the other end of said portion so as to engage with the adjacent side of the rail-head, a vertically disposed member secured to one end of the saddle portion so as to depend beneath the rail-head, a second member rotatably secured in the lower end of the first member so as to extend parallel with the rail beyond the side of the saddle portion, yielding means whereby the second member is held in its adjusted positions, and a blow-pipe holding socketed member adjustably secured to one end of said second member.

FRANKLIN C. HASSE.

Witnesses:

MURIEL M. GOLDSTEIN.

It is hereby certified that in Letters Patent No. 1,342,502, granted June 8, 1920, upon the application of Franklin C. Hasse, of Congress Park, Illinois, for an improvement in "Rail-Cutting Devices," an error appears in the printed specification requiring correction as follows: Page 3, line 129, claim 2, for the word "contacting" read *contracting*; and that the said Letters Patent should be read with this correction therein that the same may conform to the record of the case in the Patent Office.

Signed and sealed this 6th day of July, A. D., 1920.

[SEAL.]

M. H. COULSTON,

Acting Commissioner of Patents.
